Primary Examiner—Holly Baynham**Attorney, Agent, or Firm—David L. Volk****[57] CLAIM**

The ornamental design for an adjustable shovel head, as shown and described.

DESCRIPTION

FIG. 1 is a front perspective view of an adjustable shovel head showing my new design;

FIG. 2 is an exploded perspective;

FIG. 3 is a bottom rear perspective view thereof;

FIG. 4 is a top plan view thereof;

FIG. 5 is a left side elevational view thereof;

FIG. 6 is a right side elevational view thereof; and,

FIG. 7 is a right side elevational view thereof, showing the pin in an alternate hole.

The broken line showing of a handle is for illustrative purposes only and forms no part of the claimed design.
